REMOTE CONTROL AND DATA READ-OUT UNIT

James Teague, Glenview, Ill., assignor to Texas Instruments Incorporated, Dallas, Tex., a corporation of Delaware

Application June 27, 1957, Serial No. 46,762

Term of patent 14 years

(Cl. D26—14)

Fig. 2

Fig. 3

Fig. 4

Figure 1 is a perspective view of a remote control and data read-out unit showing my new design;

Figure 2 is a top plan view thereof, to a reduced scale;

Figure 3 is a front elevational view, to a reduced scale, taken along a line perpendicular to the face thereof; and

Figure 4 is a side elevational view thereof, to a reduced scale, the opposite side having substantially the same appearance.

The essential features of my design reside in the portions shown in solid lines on the drawings. The face portions of the drawings of Figures 1, 2 and 3 are both color coded and diagonally lined to indicate a transparent sur-

face over a colored background whereby, when selectively lighted from behind, data representation is visible therethrough.

I claim:

The ornamental design for a remote control and data read-out unit, substantially as shown and described.
